COMBINED POWERED CHUCK FIXTURE AND GUIDEWAY FOR TUBE BENDING MACHINES

Hans Schmidt, Aurora, Ill., assignor to Pines Engineering
Co., Inc., a corporation of Illinois

Filed Nov. 29, 1963, Ser. No. 77,617

Term of patent 14 years

(Cl. D55—1)

FIG. 1 is a perspective view of a combined powered chuck for tube bending machines showing my new design;

FIG. 2 is an elevational view of one end thereof;

FIG. 3 is a top plan view thereof; and

FIG. 4 is an elevational view of the back side thereof as shown in FIG. 1.

The broken line showing of hoses and fittings is for illustrative purposes only.

I claim:

The ornamental design for a combined powered chuck

fixture and guideway for tube bending machines, substantially as shown and described.
